INFANT CARRYING DEVICE

Evaline W. Dautermann and Frederic Lewis
Dautermann, St. Paul, Minn.

Application May 26, 1950, Serial No. 164,374

1 Claim. (Cl. 224—6)

1

Our invention relates to an improvement in infant carrying device wherein it is desired to provide a simple device for carrying a small child.

The need for a device for carrying small children has long been recognized. By use of such an apparatus it is possible for a mother to carry a small child and still have full use of the arms and hands. Several devices have been previously designed to accomplish this result. However, these devices employed certain features which sometimes rendered them either difficult to use or uncomfortable for the infant.

A feature of the present invention resides in the provision of a carrying device which encircles the body of the infant so as to avoid all danger of injury due to falling from the carrier. At the same time, this device is so designed that it may be quickly opened up so that the infant may be placed in the carrier or removed therefrom with a minimum of difficulty.

A feature of the present invention resides in the provision of a carrier having a relatively rigid seat board embodied in the base of the carrier and in shaping this seat so as to project forwardly between the legs of the infant. The carrier is so designed that the projecting portion of the seat may rest upon the hip bone of the person carrying the infant so that the body may assist in the support of the carrier.

A further feature of the present invention lies in the provision of a carrier having a pair of spaced leg openings through which the legs of the infant may project and having a separable fastener extending from one leg opening to the upper extremity of the carrier. By opening this separable fastener the portion of the carrier normally encircling the body of the infant may be opened up to greatly facilitate the insertion or removal of the infant.

A further feature of the present invention lies in the manner in which the rigid seat member may be inserted and removed. The seat of our device is arranged in a pocket which opens toward the rear wall of the carrier. Thus while the carrier is in use, it is physically impossible to remove the rigid seat reinforcing member. When the carrier is not in use, the reinforcing member may be easily removed. In view of the location and arrangement of the pocket it is not necessary to provide means for closing the pocket or holding it closed.

An added feature of the present invention lies in the provision of straps which anchor near the rear of the seat and are connected to the

2

body wall of the carrier to incline forwardly and upwardly. As a result of this structure the strap may conveniently extend over the shoulder opposite the side of the body against which the carrier rests without twisting the strap and without uncomfortable strain or tension against any part of the body.

An added feature of the present invention lies in the provision of a separate strap encircling the back of the carrier body and free therefrom. This strap is designed to reinforce the body wall and also to permit the wall and reinforcing strap to flex independently.

These and other objects and novel features of our invention will be more clearly and fully set forth in the following specification and claim.

In the drawings forming a part of our specification:

Figure 1 is a front perspective view of our infant carrier showing in general the construction thereof.

Figure 2 is a rear perspective view of the same. Figure 3 is a plan view of the seat reinforcing member.

Figure 4 is a sectional view through the seat at the center portion thereof.

The carrier is indicated in general by the letter A. The carrier is provided with a body wall 10 which is arranged to be substantially oval in form when the carrier is in use. The body wall 10 is of sufficient height to prevent an infant from falling from the carrier and will accommodate an infant from the time it is old enough to hold the head erect until after it is large enough to walk about freely. The upper edge of the body wall 10 is bound with tape as indicated at 11, or is otherwise finished to provide a smooth well appearing edge. The lower edge of the body wall is stitched marginally as indicated at 12 to a bottom panel 13 of fabric. This bottom panel 13 is of the same general shape as the seat reinforcing member 14 illustrated in Figure 3 of the drawings.

Two rounded notches 15 and 16 are provided in the body wall 10 to act as leg openings for the infant. These notches 15 and 16 are spaced to provide an intermediate strap 17 which connects with the bottom panel 13 by stitching 18 as indicated in Figure 4 of the drawings. The marginal edges of the notches 15 and 16 are bound with tape as indicated at 20 and 21 respectively, so as to provide a smooth finished edge at the bottom of the carrier.

As indicated in Figures 1 and 3 of the drawings, the center portion of the bottom panel 13

projects forwardly, the bottom panel being cut to provide spaced notches 22 and 23. These notches form continuations of the notches 20 and 21 and the strap 17 connects with the forwardly projecting portion of the bottom panel between the notches. This construction permits the central projecting portion of the carrier to contact the body of the person carrying the infant so as to space the major portion of the carrier from the body and so that the carrier may gain support by the hip bone of the person carrying the infant.

A seat panel 24 overlies the bottom panel 13 and is connected thereto along opposite sides and along the front edges of the two panels. 15 The seat panel 24 is connected to the bottom panel 13 throughout the notches 22 and 23 and also by the stitching 19 connecting the central strap 17 with the bottom panel 13. The sides of the seat panel 24 are also connected to the 20 bottom panel by the stitching 12, which connects the bottom panel to the side wall 10. However, the entire rear edge of the seat panel 24 is free of the bottom panel 13 and is provided with a bound edge 25 which is somewhat longer than 25 the seat reinforcing member 14 illustrated in Figure 3. In other words, the pocket 26 formed between the seat panel 24 and the bottom panel 13 is sufficiently wide to permit insertion and removal of the reinforcing member 13, but the 30 opening of this pocket 26 is adjacent to the rear wall of the carrier. As a result while the infant is being carried it is impossible to remove the reinforcing member and this member may only be removed when the carrier is not in use. 35 This arrangement also eliminates the necessity of snaps, buttons, or fasteners for holding the pocket closed, as the opening of the pocket is normally closed by the rear wall of the carrier.

The seat reinforcing member is designed to 40 fit within the pocket 26 and is shaped similarly to the pocket. The reinforcing member 14 is shown as having a rounded rear edge 27 which is curved as indicated at 28 and 29 at its junction with the generally parallel ends 31 and 32. 45 A central projection 33 is provided at the forward edge of the seat, this projection acting as a spacer between rounded notches 34 and 35. The notches 34 and 35 correspond to the notches 22 and 23 in the bottom panel, while the projection 33 corresponds with the forwardly projecting center portion of the bottom panel. It is the projection 33 which usually supports the center portion of the carrier at its point of engagement with the body of the person carrying the 55 infant. The projection preferably rests just above the hip bone.

A separable fastener of the hookless type is indicated at 36 and the wall 10 is vertically split at this point. The split or separation in the 60 wall 10 extends from the upper edge of the carrier into communication with the notch 21. The fastener is of the separable type which permits the body to be entirely disconnected along the line of separation. Accordingly the body wall 65 10 may be opened up to permit easy access and removal of the infant.

The body 10 is supported by a pair of straps as best illustrated in Figures 1 and 2 of the drawings. One strap 37 is anchored in the seam 70 between the side wall 10 and the bottom panel 13 and is held in anchored position by the stitching 12. As best shown in Figure 2, the strap 37 is secured to the side wall 10 by stitching 39 which extends to a point spaced from the 75

upper end of the wall 10. The strap 37 inclines forwardly and upwardly at a substantial angle to the vertical so that the strap may extend flatly over the back of the person carrying the infant and over the shoulder opposite the side against which the carrier is supported. As indicated in these figures, the strap 37 extends through the end of a snap fastener 40 and is doubled back upon itself for attachment with an adjustment fastener 41. By changing the position of the fastener 41, the length of the strap 37 may be easily regulated.

The second strap 42 is also anchored at its lower end between the marginal edge of the side wall 10 and the inturned marginal edge of the bottom panel 13 and is held in place by the stitching 12. The strap 42 inclines upwardly and forwardly as shown in Figure 1 and is secured to the carrier wall 10 by stitching 43. The upper end of the strap is doubled back upon itself at 44 and is secured in this doubled position to support the connecting ring 45. The snap fastener 40 is detachably engageable with the member 45 so that the two straps may be connected or disconnected.

A strap 46 is terminally connected at one end to the strap 42 as indicated in Figure 1 of the drawings, and is terminally connected at its other end to the strap 37. The strap 46 is preferably not connected to the wall 10, except at its extremities so that the wall may flex relatively to the strap. The strap 46 acts as a reinforcement for further support of the infant.

When in use the hookless fastener 36 is opened to permit the insertion of the infant into the carrier. When the infant is in place with one leg projecting through each leg opening, the fastener 36 is closed. The strap 37 extends over the shoulder of the person carrying the device opposite the side against which the carrier rests. When in place the center projection 33 of the base reinforcing member extends against the side of the person carrying the infant, this projection usually lying over the hip bone to provide added support.

When it is desired the device may be washed by merely removing the reinforcing board 14 and if desired removing the buckles and snaps, although the removal of these latter objects is not essential. However, when the device is in use the seat can not be inserted or removed. The separable fastener can not be readily disengaged by the infant. However, the strap arrangement is such that the rear wall of the carrier remains in taut position at all times, while the carrier is in use, even if the fastener 36 is disengaged.

In accordance with the patent statutes, we have described the principles of construction and operation of our infant carrying device, and while we have endeavored to set forth the best embodiment thereof, we desire to have it understood that this is only illustrative thereof and that obvious changes may be made within the scope of the following claim without departing from the spirit of our invention.

We claim:

A baby carrier including a wall designed to encircle the body of an infant, the forward portion of the wall having a pair of spaced leg openings therein, a seat connected to said wall including a bottom panel, means securing said bottom panel marginally to the wall, a substantially coextensive upper panel, means securing said upper panel marginally along the front and

sides only to said bottom panel thereby leaving said bottom panel unattached along the rear edge thereof, said panels forming a pocket having a pocket opening directed toward the rear portion of the wall, a reinforcing member between said panels, a first carrying strap portion having one end anchored between the marginal edge of said wall and the rear edge of said bottom panel by said first mentioned securing means, a second carrying strap portion having one end also anchored between said marginal edge of said wall and said rear edge of said bottom panel by said first mentioned securing means, said strap portions extending upwardly and forwardly, additional means securing the intermediate sections of said strap portions to said wall, detachable means connecting the other ends of said strap portions, and a single separable fastener in said wall extending from the upper edge thereof to one of said leg openings.
